UNITED STATES PATENT OFFICE.

EDWIN E. ANGELL, OF BOSTON, MASSACHUSETTS.

METHOD OF PROTECTING COMMERCIAL PAPER.

No. 869,823.

Specification of Letters Patent.

Patented Oct. 29, 1907.

Application filed April 4, 1907. Serial No. 366,437.

To all whom it may concern:

Be it known that I, EDWIN E. ANGELL, of Boston, in the county of Suffolk and State of Massachusetts, have invented certain new and useful Improvements in Methods of Protecting Commercial Paper, of which the following is a specification.

This invention has for its object to indicate indelibly and inefaceably the monetary value of checks, bonds, stock certificates and similar commercial papers, so that any attempt at erasure or alteration of the characters formed in, on, or of the paper will destroy the paper so effectually as to render absolutely impossible the successful consummation of any attempt to increase the amount indicated on the paper.

15 In carrying my invention into effect I indicate the value represented by the paper by altering the appearance of the paper over areas of any desired amplitude which entirely surround spaces that are left blank, the edges of the altered portion of the paper adjacent the blank spaces being so shaped as to give such blank spaces the contour of the figures, letters or other conventional characters which they are intended to represent. This alteration of appearance is produced by coloring, cutting, displacing or corrugating the paper, 25 or by a combination of these operations. At the same time, the action on the paper which causes the alteration referred to also so weakens or destroys the continuity thereof that it cannot be made sufficiently smooth or restored nearly enough to its original strength 30 as to permit of a different character being designated thereon in place of the original character. These altered portions are preferably inked so as to define more clearly the outlines of the characters and to eliminate still further the possibility of altering the characters.

35 In the accompanying drawings I have illustrated one embodiment of a device for carrying out my invention as the same is hereinafter described and claimed.

In the drawings,—Figure 1 represents a central longitudinal vertical section through the device or apparatus. Fig. 2 represents a cross section on line 2—2 of Fig. 1. Fig. 3 represents a cross section on line 3—3 of Fig. 1. Figs. 4 and 5 represent detail elevations of two forms of impression members by which the characters are formed in, of, or upon the sheet. Fig. 6 represents a detail sectional view of one of the character forming members. Fig. 7 represents an elevation of a part of a sheet of paper, showing the appearance thereof after the characters have been formed thereon.

45 The same reference characters indicate the same parts in all the figures.

50 The base of the frame is represented by 10, said base having a table or surface 11 for the check or paper 12 that is to be embossed and printed. A suitable cover is indicated at 13. The frame is provided with a horizontal bracket 14 a slight distance above the level of the table surface 11. Within the base are bearings 15 for

a tubular shaft or sleeve 16 to which is rigidly secured a rotary printing table or plate 17. Secured to the rear end of the tubular shaft or sleeve is a gear 18.

A tubular arm or lever 19 is provided with ears 20 which are pivoted at 21 to the sides of the base. Said lever is formed with lateral arms 22 (see Fig. 2), and the bracket or frame portion 14 is provided with sockets or hollow pieces 23 containing springs 24 and plugs or plungers 25 which are pressed upward by the springs against the under sides of the arms 22 so as normally to hold the lever raised in the position indicated in Fig. 1. The arms 22 are also provided with uprights 26 at their outer ends, to which are pivoted at 28 arms 27 carrying inking pads or rollers 29. Springs 30 are connected with the arms 27 and to a pin 31 projecting from the top of the lever so as normally to hold the inking rolls in contact with the circumference of the upper printing plate or character forming member, which will be presently described.

75 A shaft 32 is rotatively mounted in the tubular lever 19 and carries rigidly upon its end a gear 33 which meshes with the gear 18 at a point in line with and between the pivots 21 of the lever 19, so that movements of the said lever will not throw the gears out of mesh 80 and will have no other effect than to move one slightly out of the plane of the other.

Secured to the shaft 32 is the upper printing plate 34 which has a cylindrical external operating surface so formed as to impress the paper. A handle 35 is secured to the front end of shaft 32 as is also a disk or dial 36 provided with suitable characters which, by reference to a stationary indicator 37, indicates the character which will be shown upon the sheet when any impression is to be made by the printing plates. 90

From the top of the bracket or frame 14 is an upright 38 having a stop pin 39 to limit the upward movement of the lever. A horizontal tubular member 40 at the upper end of the upright contains a pin or detent 41 which is normally pressed outward by a spring 42, and 95 has a convex or conical outer end adapted to enter any one of a series of holes 43 in the gear 33. The pin 41 is recessed on the under side at 44 so as to receive a stop screw 45 which prevents the pin being wholly ejected from the tubular member 40 by the spring. Preferably 100 the diameter of the pin 41 is slightly larger than that of the holes 43 so that only the tapered end enters these holes, thus enabling the gear to be rotated by the handle 35 by the employment of sufficient force to retract the pin, owing to the pressure on its beveled end of the 105 edge of the hole. The end of the pin, however, slips into each of the holes as the latter comes into line with it, and so tends to arrest the gear and hold it stationary.

110 On each side of the lower printing plate or rotary table 17 is a roller or pad 46, these rollers being carried by arms 47 pivoted at 48 to the base and pressed against the periphery of the printing table by springs 49.

There is an adjustable stop 50 in the frame against which any one of a series of stops 51 carried by the upper printing member 34 is adapted to contact so as to limit the amount of movement of the members toward each other. At 52 is shown a wheel presser-foot mounted upon a stud or pin 53 carried by a movable member so as to hold the paper against the surface of a feed wheel 54.

The feed wheel above mentioned is mounted on pin 55 secured to the frame and to it is secured a pinion 56. Said pinion meshes with another pinion 57 fast upon a shaft 58 which passes through the central bore of the tubular shaft or sleeve 16. On the rear end of shaft 58 is secured a ratchet wheel 59 adapted to be actuated 15 by the movement of the lever 19 toward and away from the lower printing plate 17. The mechanism by which this actuation is produced consists of a pawl 60 pivoted to the lower end of an arm 61 and drawn toward the latter by a spring 62. The arm is carried by a rock-shaft 63 upon which is also secured an arm 64 (see Fig. 2), the end of which engages a perforated ear 65 which projects downward from the tubular arm 19. Through these connections each downward movement of the lever withdraws the pawl from a tooth of the ratchet 25 and upon the upward movement of the lever the springs 24 cause the pawl to be advanced and to turn the ratchet 58 through the space of one tooth, thereby turning the feed wheel sufficiently to advance the paper far enough to receive a new impression. A detent 30 pawl 70 engages the ratchet to prevent retrograde movement.

In bearings carried by the bracket 14 is mounted a rock-shaft 66 (Fig. 2) having a finger piece 67, and provided with another arm 68 on which the pressure wheel 35 52 before mentioned is mounted. A spring 69 is coiled about the shaft 66 and connected with the arm 67 and a suitable fixed part of the frame so as to press the wheel 52 downward upon the paper. Adjustable gages for the edge of the paper are shown at 71.

40 The character of the printing or character-forming members is illustrated in elevation in Figs. 4 and 5, and in section in Fig. 6. The surfaces of these printing members which come into contact with the paper are grooved and ribbed, forming sharp-edged ridges *a* alternating with angular depressions *b*, these being so spaced on the co-operating members that the ridges of one enter the grooves of the other, and thereby indent, corrugate, or partly cut through the paper. In the upper printing member are formed depressions or cavities *c* which have 45 the shape or reversed figures, letters or other conventional characters, and are contained entirely within the boundaries of the rigid surfaces. The ridges and grooves *a* and *b* extend to the edges of the cavities *c*, and terminate abruptly. Thus when the printing plates are 50 pressed together on opposite sides of the paper, the latter is offset and penetrated or cut through more or less completely where it is pressed upon by the ridges, but it is not altered in any way upon those portions which lie under the cavities *c*. Thus each impression upon 55 the paper causes the character to be outlined thereon by the abrupt termination of the cuts or ridges, so that each character is represented by a smooth blank space, while the paper on all sides of this blank space is corrugated, its continuity destroyed, and its strength 60

70 sufficiently deep so that the paper is greatly stretched when compressed between the printing plates, and this has the effect either of wholly cutting through the sheet on the lines of the ridges, or of stretching and somewhat pulling apart the fibers so that the paper is much weakened and the surface roughened and entirely altered in appearance. This causes the unchanged areas in the shape of the characters to become plainly apparent and to be easily read. The effect is intensified when ink is applied by the plates, because then the grooves receive 75 color contrasting with that of the sheet, whereby the points at which the ridges depositing the color terminate are very sharply defined.

80 The roughening and partial destruction of the paper renders it practically impossible for a dishonest person to increase the original indicated value of the paper, for the reason that the displaced and partially separated fibers cannot be again smoothed down to give the sheet its original texture, and thus a new impression over a former one, of which the effacement had been attempted, will show evidence of tampering sufficient to raise suspicion. When the ink is deposited at the same time that the paper is impressed, the loosening and separation of the fibers enables the ink to be partly soaked up and to penetrate into the interior of the sheet. At the 85 same time the paper is so weakened that it will not stand more than a very little rubbing without tearing away. Thus it is absolutely impossible to remove the ink and to obliterate the first impression sufficiently to enable a subsequent impression to be made on the same 90 surface without detection. The removal of an entire character and substitution bodily of a piece of paper carrying a different one also is impossible; first, for the reason that the new piece could not be made of the right thickness and formed with corrugations to match 95 and align with those of the sheet, except by the merest accident, and second, that there is not enough body and strength left in the sheet after the partial destruction hereinbefore described to permit of firmly uniting the substituted piece with the remainder of the sheet. 100

105 The lower printing plate may be made either as shown in Fig. 4, or in Fig. 5, that is, with a continuous series of uninterrupted ridges, or with cavities having the form of the conventional characters. In the latter case the printing members are adjusted so that the characters of one will exactly register with those of the other, the characters in the lower member 17 appearing as on the sheet, while those of the upper member are reversed. 110

115 I am aware that hitherto commercial paper has been printed upon by means of types which cut or corrugate the paper over the surfaces represented by the characters, and also that the paper has been punched so as entirely to remove small portions thereof, to represent the characters, but in all cases where the character alone is printed, the paper may be manipulated and certain characters substituted, such as a "5" for a "3", with very slight danger of detection, while when bits of the paper are punched out, it is a simple matter by taking pains, to replace the punchings and to give the paper exactly its previous appearance. When commercial paper is protected by my method above described, however, there is no portion of the sheet actually removed, so that therefore it is impossible to substitute fresh bits in place of the injured portions; furthermore since the whole area of the sheet surrounding. 120 125 130 135

the character is defaced or destroyed, it is not possible to print another character over one originally formed without greatly changing the appearance of the sheet.

I claim:—

5. 1. The method of protecting commercial paper, which consists in stretching or breaking the fibers of the entire field of the paper surrounding areas having the form of conventional characters. 40
10. 2. The method of protecting commercial paper, which consists in destroying the continuity of the surface of the paper on all sides of areas having the form of conventional characters, which are left intact, said destruction including the entire field between the characters. 45
15. 3. The method of protecting commercial paper, which consists in distorting the surface of the entire field of the paper surrounding blank areas having the form of conventional characters, while leaving all the particles of the paper attached to the sheet. 50
20. 4. The method of protecting commercial paper, which consists in weakening, without removing, the entire field of the paper immediately surrounding blank portions in the form of conventional characters. 55
25. 5. The method of protecting commercial paper, which consists in weakening, without removing, the entire field of the paper immediately surrounding blank portions in the form of conventional characters, and depositing ink on the weakened portions of the paper. 60
30. 6. The method of protecting commercial paper by forcing ink into, and simultaneously distorting and weakening, the entire field of the paper on all sides of a portion thereof, having the form of a conventional character, which is left smooth and clear. 65
35. 7. The method of protecting commercial paper, consisting in corrugating the paper to form alternate ridges and depressions, interrupting the ridges and depressions to leave blank smooth intermediate spaces shaped as conventional characters, the said ridges and depressions occupying the entire field between characters, and inking the bottoms of the depressions. 70
8. The method of protecting commercial paper, consisting in pressing the paper between printing plates having alternately opposed sharp ridges and depressions, one or both of said plates having recesses shaped as conventional characters or the reverse of characters, the said ridges and depressions occupying the entire field between the characters, and forcing ink into the paper by means of such ridges. 75
9. The method of protecting commercial paper which consists in forming a character out of the original paper by destroying the continuity of the paper, but without removing the same, immediately and entirely around the character. 80
10. Commercial paper having smooth blank areas shaped as conventional characters, the entire field between the characters being occupied by weakened and distorted portions of the paper. 85
11. Commercial paper having smooth blank areas shaped as conventional characters, the entire surface of the paper between and surrounding said areas being inked and the fibers thereof stretched and weakened. 90
12. Commercial paper having smooth blank areas shaped as conventional characters having surrounding portions and the entire intermediate field corrugated to form alternating ridges and depressions, said ridges and depressions terminating at the edges of the said spaces. 95

In testimony whereof I have affixed my signature, in presence of two witnesses:
